DOORKNOB

Hayes O. Scott, Flint, Mich., assignor to The Engineered Products Company, Flint, Mich., a corporation of Michigan

Application November 3, 1954, Serial No. 32,938

Term of patent 14 years

(Cl. D50—3)

Figure 1 is a perspective view of a doorknob embodying my new design.

Figure 2 is a side elevation of the doorknob.

Figure 3 is a sectional view of the doorknob.

Figure 4 is a top plan view of the doorknob.

I claim:

The ornamental design for a doorknob, substantially as shown.
